UNITED STATES PATENT OFFICE

HAROLD H. MARTIN, OF PORTLAND, OREGON, ASSIGNOR TO RATE SERVICE BUREAU, A PARTNERSHIP COMPOSED OF HAROLD H. MARTIN AND THE FIRM OF DIMM AND SONS, OF PORTLAND, OREGON, AND COMPOSED OF JOHN C. DIMM AND WALTER R. DIMM

TEMPORARY FILING MEANS

Application filed May 27, 1929. Serial No. 366,283.

My invention relates to means for classifying and segregating commercial and legal papers and the like, preliminary to being permanently filed or recorded.

5 In every office in which there is a considerable quantity of correspondence, invoices, orders and the like to be filed, it has been found convenient to first preliminarily segregate and classify the same before they are 10 permanently filed. The same preliminary classifying is desirable where a large number of legal papers or documents are temporarily filed for later recording.

Therefore, the principal object of my invention is to provide effective and convenient means for such preliminary segregation or classification, in order that time will be saved and the accuracy of the filing system promoted, by the instituting of a safe and 20 convenient auxiliary system of filing. Further, to provide such a preliminary filing means that it will recommend itself to the office help and will be voluntarily used by them, thereby promoting the efficient and intelligent performance of their work.

A further object of my invention is to provide a simple, durable, inexpensively made, segregating and classifying file for the purpose stated.

30 To this end my invention comprises a binding strip of flexible material to which is secured a plurality of semiflexible, elongate, separator strips, fastened to the binder strip in such a manner as to overlie one the other, and so that the front ends of the separator strips progressively project one below the other; and on such projecting ends I provide identifying means, in that way to aid the segregation and classification of the 35 papers, which in practice are placed between the said separator strips.

With the elements of my segregating and classifying file composed and arranged as mentioned, the back of the file will lie flat 40 on the desk and no undue strain will be imposed upon the binding strip.

The details of construction of my file and its mode of operation are hereinafter fully described with reference to the accompanying drawings.

In the drawings:

Fig. 1 shows a side elevation of my temporary file and illustrates the relative arrangement of the separator strips when assembled;

55 Figs. 2, 3 and 4 show in perspective views, respectively, how each separator strip is bound to the binding strip;

Fig. 5 shows the binding strip apart from the remainder of the file;

60 Fig. 6 shows the details of construction of the binding strip and the auxiliary tabs connecting the separator strips thereto; and

Fig. 7 shows a modification of the construction of my file in which two separator 65 strips are bound to the binder strip at a time.

Referring now to the figures, my invention comprises an elongate binding strip *a* of suitable flexible material such as leather or imitations thereof, the binding strip being divided by transverse slits *b* along its opposite edges into lateral, parallel tabs *c* and larger end tabs *d* of substantial width, see Fig. 5. Similar separator strips *e* of equal length, of press board or other semiflexible material, 70 are secured to the binding strip *a* in progressive order so that each strip will project beyond the other.

In assembling the above described parts, the first separator strip *e* is laid on and cemented to the binding strip *a* as illustrated in Fig. 6, and the tabs *d* are folded over and also cemented to the said separator strip. A metal fastener *h* comprising a cross-head 80 *h*' and perpendicular pointed members *h*2 is then inserted from the underside of the binding strip and through the separator strip between the ends of the folded-over tabs *d* and the perpendicular members of the fastener *h* are then bent over laterally as shown 85 in Fig. 2.

The next separator strip *e*2 is then laid on and cemented to the binder strip so that the next adjacent narrow tabs *e* may be folded 90 over the end of the said strip, Figs. 2 and 3, and also cemented to it. Another metal fastener *h* is inserted from the underside and through the separator strip *e*2 and between the ends of the tabs *e* similarly to the 95 100

method of securing the separator strip e' to the binding strip.

Other separator strips are then secured to the binder strip a by the successive tabs c and metal fasteners h in a like manner, until my temporary file is entirely assembled with any desirable number of the separator strips bound together as illustrated in Fig. 1.

Suitable notations are provided on the free ends of the separator strips as at m for identifying each strip according to the system of classification desired.

Outer coverings j, j' of leather or suitable imitations are preferably cemented, respectively, on the under side of the separator strip e' and on the upper side of the last or upper separator strip e , to provide a finished article and to protect the heads of the fastening elements h . A supplementary binding portion $j2$ is also cemented about the end of the file.

By this construction and arrangement I have thus provided a temporary file between the separator strips of which commercial or legal papers may be segregated or classified preliminary to being permanently filed or recorded.

For example, if a mass of correspondence is to be classified alphabetically, the free ends of the separator strips having been provided with suitable alphabetical notations, the individual papers may be temporarily inserted between the appropriate strips as they come into the filing room or they may be allowed to accumulate to be later classified and then from which the correspondence so classified may be transferred to the permanent files with accuracy and dispatch. By using my file it will not then be necessary for the filing clerk to go back and forth from one file to another, but he may file all the "A's" then the "B's" and so on, or if they are to be recorded, the pages of the register in use need not be turned back and forth in searching for the proper place for each one of a number of documents.

Referring now to Fig. 7 I have shown a modification of my invention in which I have found it convenient to bind two separator strips $e3$ and $e4$ at a time to a binder strip a' similar to the binder strip a except that the tabs c' are equal in width to two of the tabs c previously described, thus strengthening the binding of the separator strips. The first separator strip e' is bound to the binder strip a' the same as before, but the successive separator strips $e3, e4$ are bound in groups of two. The separator strip $e4$ being shorter than the strip $e3$, so that the end of the latter will project beyond the former in order to provide visible spaces for suitable notations.

I have also found it desirable in this modification to use fastener elements in pairs. In other respects this form of my file is the same and its use is identical with the other form of my invention.

I claim:

1. A temporary segregating and classifying file comprising, an elongate binding strip of flexible material, the lateral edges thereof being divided by transverse slits into a plurality of relatively narrow tabs, a plurality of semi-flexible elongate separator strips of substantially lesser width than said binding strip, the said slotted lateral projections of the tabs being folded over the lateral edges of the separator strips at the inner ends of the latter and cemented thereto respectively, auxiliary fastening means securing the inner ends of said separator strips respectively to the binding strip, said fastening means located in alignment with the tabs of the binding strip, whereby the said separator strips are arranged to overlie one the other and so that the front ends thereof are successively projected one below the other and identifying means provided on said projecting ends of the separator strips.

2. In a temporary segregating and classifying file, an elongate binding strip of flexible material, the lateral edges thereof being divided by transverse slits into a major tab and a plurality of relatively narrow auxiliary tabs, a plurality of semi-flexible elongate separator strips of substantially lesser width than said binding strip, the said major tabs of the binding strip being folded over the lateral edges of the bottom separator strip and cemented thereto, and the said auxiliary tabs of the binding strip being fastened in like manner to the remaining separator strips respectively, auxiliary fastening means securing the inner ends of said separator strips respectively to the binding strip, said fastening means located in alignment with the tabs of the binding strip, whereby the said separator strips are arranged to overlie one the other and so that the front ends thereof are successively projected one below the other.

3. In a temporary segregating and classifying file, an elongate binding strip of flexible material, the lateral edges thereof being divided by transverse slits into a plurality of relatively narrow tabs, a plurality of semi-flexible elongate separator strips of substantially lesser width than said binding strip, the said slotted lateral projections of the tabs being folded over the lateral edges of the separator strips at the inner ends of the latter and cemented thereto respectively and auxiliary fastening means securing the inner ends of said separator strips respectively to the binding strip, said fastening means located in alignment with the tabs of the binding strip.

4. In a temporary segregating and classifying file, an elongate binding strip of flexible material, the lateral edges thereof being divided by transverse slits into a plurality of relatively narrow tabs, a plurality of semi-flexible elongate separator strips of sub-

stantially lesser width than said binding strip, the said slotted lateral projections of the tabs being folded over the lateral edges of the separator strips at the inner ends of the latter and cemented thereto respectively and 5 fasteners inserted through the under side of said binding strip, in alinement with the said tabs thereof, and the said separator strips respectively at the inner ends of the latter.

5. In a temporary segregating and classifying file, an elongate binding strip of flexible material, the lateral edges thereof being divided by transverse slits into a plurality of relatively narrow tabs, a plurality of semi-flexible elongate separator strips of substantially 10 lesser width than said binding strip, the said slotted lateral projections of the tabs being folded over the lateral edges of the separator strips at the inner ends of the latter and cemented thereto respectively, pliable fasteners inserted through the under side of said binding strip, in alinement with the said tabs thereof, and the said separator strips respectively at the inner ends of the latter.

6. In a temporary segregating and classifying file, an elongate binding strip of flexible material, the lateral edges thereof being divided by transverse slits into a plurality of relatively narrow tabs, a plurality of 15 semi-flexible elongate separator strips of substantially lesser width than said binding strip, the said slotted lateral projections of the tabs being folded over the lateral edges of the separator strips at the inner ends of the latter and cemented thereto respectively, pliable 20 fasteners inserted through the under side of said binding strip, in alinement with the said tabs thereof, and the said separator strips respectively at the inner ends of the latter.

7. A temporary segregating and classifying file comprising an elongate binding strip of flexible material, the lateral edges thereof being divided by transverse slits into a plurality of relatively narrow tabs, a plurality of semi-flexible elongate separator strips of 25 substantially lesser width than said binding strip, the said slotted lateral projections of the tabs being folded over the lateral edges of the separator strips at the inner ends of the latter and cemented thereto respectively and pliable 30 fasteners consisting of a cross-head and perpendicular pointed member, the latter inserted through the under side of said binding strip, in alinement with the said tabs thereof, and the said separator strips respectively 35 at the inner ends of the latter and said pointed member bent over on the upper side of the separator strip through which inserted.

40 7. A temporary segregating and classifying file comprising an elongate binding strip of flexible material, the lateral edges thereof being divided by transverse slits into a plurality of relatively narrow tabs, a plurality of semi-flexible elongate separator strips of substantially 45 lesser width than said binding strip, the said slotted lateral projections of the tabs being folded over the lateral edges of the separator strips at the inner ends of the latter and cemented thereto respectively, pliable fasteners consisting of a cross-head and perpendicular pointed member, the latter inserted through the under side of said binding strip, in alinement with the said tabs thereof, and the said separator strips respectively 50 at the inner ends of the latter and said pointed member bent over on the upper side of the separator strip through which inserted, whereby the said separator strips are arranged 55 to overlie one the other and so that the

front ends thereof are successively projected one below the other.

8. A temporary segregating and classifying file comprising an elongate binding strip of flexible material, a plurality of semi-flexible elongate separator strips secured to the said binding strip in pairs, the strips of each pair being of unequal length and arranged so that the longer strip underlies and its front end projects beyond the front end of the shorter strip, the pairs of separator strips being arranged on the binding strip so as to overlie one on the other, so that the front ends of each pair are successively projected beyond the ends of the other pairs.

9. A temporary segregating and classifying file comprising an elongate binding strip of flexible material, a plurality of semi-flexible elongate separator strips secured to the said binding strip in pairs, the strips of each pair being of unequal length and arranged so that the longer strip underlies and its front end projects beyond the front end of the shorter strip, the pairs of separator strips being arranged on the binding strip so as to overlie one on the other, so that the front ends of each pair are successively projected beyond the ends of the other pairs, and identifying means provided on said projecting ends of the separator strips.

HAROLD H. MARTIN.
